UNITED STATES PATENT OFFICE.

ARTHUR W. WALKER, OF MALDEN, MASSACHUSETTS.

RADIATOR-JOINT.

1,108,532.

Specification of Letters Patent. Patented Aug. 25, 1914.

Application filed December 2, 1912. Serial No. 734,512.

To all whom it may concern:

Be it known that I, ARTHUR W. WALKER, a citizen of the United States, residing at Malden, in the county of Middlesex and 5 State of Massachusetts, have invented new and useful Improvements in Radiator-Joints, of which the following is a specification.

This invention relates to improvements in 10 radiators. More particularly it relates to the construction of joints in radiators such as are used in hot air furnaces, for extracting the heat of the gaseous products of combustion. While radiators made for that purpose may be of various forms, the invention 15 is here shown as it may be applied to a radiator in the form of an annular chamber through which the hot gases pass on their way to the chimney flue. Such chambers 20 are commonly made with cast iron tops and bottoms, and with sheet iron walls, these parts being held together by very long bolts which run through from top to bottom, clamping the top and bottom tightly upon 25 the edges of the intervening sheet metal. The strength which is contributed to this structure by the bolts has been deemed necessary because of the stresses to which the 30 part is subjected during shipment to the place of installation, and during installation; and yet the bolts are objectionable because if drawn tight they are liable to snap under the influence of changes of temperature, while if left loose they fail of 35 accomplishing their purpose, and also permit the putty with which the cracks are packed to work loose, thus letting the gases of combustion escape from the radiator into the 40 surrounding air which is to be used for heating the house.

It is the object of the present invention to perfect radiators of the type described by providing such a construction and joint of the sheet metal walls and cast iron tops and 45 bottoms that the structure as a whole is thoroughly strong without the use of bolts; and is thoroughly tight because a location is provided for putty, and mechanical means for holding it in place, such that the putty 50 cannot escape, and remains as a filler even though it lose its characteristic grip on the adjacent metal.

The accompanying drawings illustrate an embodiment of the invention, in which—

Figure 1 is a section through a corner of 55 the radiator showing the improved construction of joint; Fig. 2 is a diagrammatic elevation of a hot air heater, showing the joint applied thereto and showing the general relation of parts; and Fig. 3 is an elevation in section of the radiator itself, the dimensions of certain parts being exaggerated for clearness.

Referring to the drawings, Fig. 2 shows a hot air heater or "furnace" which may be 65 considered as being of any ordinary or desired type, in which 20 indicates the grate and 21 the fire-box, to which fuel is introduced through the door 22, the ashes being taken out through door 23. The radiator is 70 represented at 24, this numeral referring to the radiator as a whole. There is an entrance at 25 for the gaseous products of combustion to pass from the fire-box into the radiator; and a discharge pipe at 26 for 75 these same gases to pass to the smoke pipe leading to the chimney flue, after communicating some of their heat to the radiator walls, whence it is radiated into the air in the surrounding chamber 19. 80

Referring now to Fig. 3 it will be seen that the radiator is composed of a ring-shaped bottom 27 which rests on the top of the fire-box 21, Fig. 2, and a similarly shaped top 28, there being a vertical cylindrical 85 piece of sheet metal 29 forming the inside wall of the radiator and a similar piece 30 forming the outside wall of the radiator. These two are concentric cylinders resting on the lower casting 27 and supporting the 90 upper casting 28.

Referring now to Fig. 1 where the structure is seen in greater detail, it will be observed that the cast iron top has a relatively heavy rim 31 projecting downward, and 95 that the upper portion of the standing sheet metal is bent outward at 10 so that a ledge is formed on which rests the lower edge of the depending rim 31 of the top. This bend outward is so short that the rim 31 100 rests practically vertically over the upright portion of the cylindrical wall 30 of sheet metal. It cannot slip either inward or outward from this position because of the circu-

lar form of the higher parts of the sheet metal which rise above and surround the depending rim 31. The outer face of the rim 31 is shaped inward to form an annular recess as at 32. Above the recess it is shaped outward again as at 33; and still higher it is shaped inward to form the top of the piece 28. The sheet metal, having been bent outward to form the ledge 10, is next higher 5 bent slightly farther outward in a conical form as at 11, going straight past the recess 32 and bearing against the part 33 higher up; and still higher it is bent inward over the top 28 as at 12. By this construction the rim 31 of the top is incased above and below, at 12 and at 10, by the sheet metal; and as these holding portions 10, 12, of the sheet metal have considerable length, equaling the entire circumference of the 10 casting 28, the intensity of stress imposed by the casting thereon is relatively low, in case of any stress arising, either downward or upward, because it is spread over so much of the area of sheet metal. Moreover, any such 15 stress applied, for instance, at 10 is applied merely edgewise to the main body of sheet metal 30 so that there is a large depth of metal in the direction in which the stress is applied. In fact, a very heavy stress can 20 be applied downward on the rim 31 without collapsing the shell 30 so long as it retains its cylindrical shape. As there is no occasion, in practice, for the shell 30 to be dented or knocked out of cylindrical form it ordi- 25 narily retains this strength throughout its life. So likewise, in case of any stress arising in the opposite direction, the lip 12 of the sheet metal has been bent over upon the top 28 by a mallet or other suitable forming 30 tool; and being bent down tight constitutes so short a stub or hook that it is adequate to resist any upward stresses that are apt to happen that would tend to loosen the top 28, such stresses being transmitted as tensile 35 stresses through the part 11 to the part 10 and 30 of the sheet metal, and being transmitted through a practically straight part 11, which consequently is not deformed no matter how great the tensile stress may be- 40 come. If the part 10 is deformed by such stress no injury of importance will result, owing to the putty filling. The rim 31 fitting down on the ledge 10, and the flange 12 fitting down on the rim 31, coöperate to make 45 a rather tight metallic connection with a double seal to prevent leakage of gases from the inside of cylinder 30 out between it and the top 28 into the air chamber 19 of the heater; but the invention comprises another 50 feature which makes this wall tight with certainty. This is the provision of the recess 32 and the inclosing of it by the straight conical section of the sheet metal 11, and the filling of this space between 32 and 11 with 55 putty or other suitable calking material 13.

In the calking of radiator joints mere adhesion between the putty and the two surfaces of a crack is ordinarily relied upon, the putty being free to fall out if it gets loose, as in fact it does more or less with 70 lapse of time, so that old "furnaces" or hot air heaters traditionally emit coal gas and other offensive gases into the air which is distributed to the living rooms of a house. In the present construction the grip of the 75 putty may be lost entirely either owing to disintegration or owing to the shocks received by the radiator in handling, in transit, or in installation, and yet that putty is held mechanically in place above the ledge 80 10 and below the projection 33 so that gases cannot blow through from the radiator into the space outside; and this putty receptacle is maintained tightly closed by the bending of the lip 12 above it over the rim projection 85 33. In fact, however, the lip 12 prevents the rim 31 and putty holding wall 32 from shifting upward with respect to the sheet iron 11, and the ledge 10 prevents them from shifting downward, so that any 90 shocks that are received during transportation and handling do not destroy the hold which the putty has on surfaces 11 and 32 and the radiator can enter upon its term of 95 service after being installed in as good condition as when the joint was made at the factory.

The manufacturing process consists in first forming the ledge 10, then in filling or calking the recess 32 and bending the portion 11 up to close it and then fastening the whole by hammering the annular lip 12 down in place with a mallet. A similar joint is made at each end of each cylinder. The radiator as a whole is thus free from 105 bolts, and yet is stronger and tighter, and less changeable under handling or with lapse of time, than any construction of bolt-fastened radiator known to me.

I claim:

1. A joint for radiators, comprising a cast metal end piece, formed with a recess in its outer side; and a sheet metal side having its end portion bent to form a ledge on which the end piece rests and extended to 115 cover the outer side of said end piece and terminating in a lip bent over the end piece; and calking material filling said recess in the end piece and inclosed by the sheet metal extending over the outer side of the end 120 piece.

2. A joint for radiators, comprising a round thin cast metal end piece, formed with a thick marginal rim with a recess in its outer side; and a cylindrical sheet metal side having its end portion bent to form a ledge on which said rim rests and extended to cover the outer side of said rim and terminating in a lip bent over the said rim; and calking material filling said recess in 130

the rim and inclosed by the sheet metal extending over the outer side of the rim.

3. A joint for radiators, comprising a cast metal end piece, formed with a recess located approximately at its periphery; a sheet metal side piece having its end portion bent to form a ledge, on which the said end piece rests approximately at its said periphery, and extended to cover the said recess and periphery, and to engage the said end

piece adjacent to said periphery, to hold said end piece in place; and calking material filling said recess and inclosed by the sheet metal extending over it.

Signed by me at Boston, Mass., this 15 twenty-seventh day of November, 1912.

ARTHUR W. WALKER.
